MAGNETIC HAND TOOL

Robert Ullman, New York, N. Y., and Fred Brauner, Laurelton, N. J.; said Brauner assignor to said Ullman

Application May 9, 1945, Serial No. 592,892

3 Claims. (Cl. 294—65.5)

The present invention relates to magnetic hand tools, and, more particularly, to permanently magnetized hand tools especially adapted for use in removing shavings and chips from screw threads and the like.

It is an object of the present invention to provide hand tools of the character described which are of strong, permanent magnetic character.

It is also an object of the present invention to provide tools of the character described in which the operative portion of the tool is not permanently magnetized and may, therefore, be formed of strong, non-brittle, durable tool steel or the like.

It is another object of the present invention to provide hand tools of the character described which exert a maximum of magnetic force through the operating end thereof.

It is a further object of the present invention to provide hand tools of the character described which may be readily adapted for use in removing iron and steel shavings from screw threads, either internal or external, or from other narrow spaces, grooves or crannies that are difficult of access, such as from the spaces between rails on a railroad track, or the like.

It is a still further object of the present invention to provide permanently magnetized hand tools of the character described which are of simple construction, economical to produce, are positive in action and easy and convenient to manipulate and use and which possess many other superiorities and advantages, some of which will hereinafter be more fully set forth and others of which will become readily clear from the accompanying drawing and the description following.

In the making of screw threads upon iron and steel objects, a certain amount of shavings or chips inevitably remain in the thread grooves formed which have to be removed before the threads may be used. These shavings are generally covered with oil from the oil used on the threading tools and, therefore, adhere to the thread surfaces. They are, therefore, difficult to remove. The methods for removing such shavings, as heretofore used, such as brushing or compressed air, have not been found completely satisfactory and efficient; the latter comprising a source of danger to the operator's eyes.

To overcome the foregoing difficulties and to make possible rapid, complete and effective removal of shavings and chips from screw threads, we have devised a new and novel magnetic hand tool capable of entering into the thread grooves

and removing the shavings therefrom by magnetic attraction.

Generally stated, such tool comprises a handle-enclosed permanent magnet and a non-magnetized tool member secured to such handle and provided with a sharp end capable of wiping screw-thread grooves or entering into other, similar narrow spaces difficult of access. A maximum of magnetic flux is provided through the 10 tool portion by means of a steel cap fitting over a pole end of the permanent magnet and engaging an end of the tool to concentrate and direct all of the lines of magnetic force through the tool, thereby providing the tool with a maximum 15 of magnetic force and a maximum of magnetic operating efficiency.

One embodiment of a tool of the present invention is shown in the accompanying drawing. It is to be understood, however, that such embodiment is shown by way of illustration only, to make the principles and practice of the present invention more readily comprehensible, and is not intended in any way to limit the invention to the specific details of construction shown.

25 In the drawing:

Fig. 1 is a view in elevation and partly in section of one embodiment of a permanently magnetized hand tool of the present invention as particularly adapted for the removal of shavings 20 or chips from screw threads or from other narrow spaces difficult of access; and

Fig. 2 is an end view of the same, viewed from the tool end thereof.

Referring more specifically to the accompanying drawing, the hand tool of the present invention may comprise a handle portion consisting of an outer shell or casing 10, of a non-magnetic material, such as a plastic material or wood or a non-magnetic metal, as aluminum, copper, or 35 the like. The shell 10 is open at one end and has snugly fitted therein the permanent magnet 11, which may be made of any of the suitable high magnetic alloys conventionally used for the purpose.

40 The relative dimensions of the shell or casing 10 and permanent magnet 11 are such that a polar end of the magnet 11 projects from the casing and its surface is exposed to receive directly thereon and to hold frictionally and tightly 45 thereon the cap 12, which may be formed of any good magnetic flux conducting metal, such as carbon steel.

The cap 12 is provided, on its roof portion, with 50 an opening 13 into which may be set one end of 55 an operative tool element, such as the rod 14.

Such rod may be formed of any suitable magnetic conductor material, such as steel, and may be firmly connected to the handle and held in position thereon by the cap 12, as by means of the reduced end 15, fitting into the opening 13 and riveted against the interior edges of such opening, as at 16.

To form the shaving removing tool of the present invention, the free end of the rod 14 may be offset sideways, as at 17, and the offset end provided with a knife edge or point 18 adapted to fit in a groove or slot to contact the shavings or chips that may be present therein. The size of the offset 17 may be modified to conform to the width of the threaded opening, when intended for use on internal threads so as to permit its insertion within the threaded opening and to have its edge 18 wiped against the grooved walls thereof.

It will be readily apparent to those skilled in the art that by the present invention we provide a hand tool which is permanently magnetized and which has, nevertheless a non-magnetized, non-brittle, magnetism conducting steel tool portion which exerts a maximum of magnetic force by reason of the concentration therethrough of substantially the entire magnetic flux of the permanently magnetized handle, through the medium of the cap connecting the tool to the handle.

It will also be readily apparent that the operative end of the tool portion of the hand tool of the present invention may be modified in size, shape and form to provide tools suitable for many

and various purposes, as for the purpose of removing metal chips from the spaces between rails on railroad tracks, and the like.

Having thus completed the description of one embodiment of the hand tools of the present invention.

What we claim as our invention is:

1. A hand tool comprising a handle, including a permanently magnetized metal core, a magnetism conducting cap frictionally engaging a pole end of the said magnetized metal core and a magnetism conducting tool member set into and retained by the said cap.

15 2. A hand tool comprising a handle, including a permanently magnetized metal core, a non-magnetic casing fitted about a portion of the said core leaving a pole end thereof exposed, a magnetism conducting cap frictionally engaging the said exposed pole end of the core and a magnetism 20 conducting tool member set into and retained by the said cap.

25 3. A hand tool comprising a handle, including a permanently magnetized metal core, a magnetism conducting cap frictionally engaging a pole end of the said magnetized metal core and fixedly retained thereon, a magnetism conducting metal rod set into and fixedly retained by the said cap, said rod having an offset free end, said free end provided with a knife edge adapted to be wiped within a thread groove.

ROBERT ULLMAN.
